Primary Examiner — Susan Bennett Hattan*Assistant Examiner* — Vy Koenig(74) *Attorney, Agent, or Firm* — Hasse & Nesbitt LLC;
Donald E. Hasse; Daniel F. Nesbitt(57) **CLAIM**

I claim the ornamental design for a box, as shown and described.

DESCRIPTION

FIG. 1 is exploded perspective view of the new design;

FIG. 2 is a side view thereof;

FIG. 3 is another side view thereof;

FIG. 4 is a rear view thereof;

FIG. 5 is a front view thereof;

FIG. 6 is a perspective view thereof;

FIG. 7 is a top view thereof; and,

FIG. 8 is a bottom view thereof.

The broken lines shown in the drawings are for illustrative purposes only and form no part of the claimed design.
